UNITED STATES PATENT OFFICE.

RALPH A. BELMONT, OF NEW YORK, N. Y.

DESIGN FOR A CASING FOR A PENDENT SWITCH.

53,483.

Specification for Design.

Patented July 8, 1919.

Application filed March 14, 1918. Serial No. 222,494. Term of patent 7 years.

To all whom it may concern:

Be it known that I, RALPH A. BELMONT, a citizen of the United States, residing at New York, in the county and State of New York, have invented a new, original, and ornamental Design for a Casing for a Pendent Switch, of which the following is a specification, reference being had to the accompanying drawing, forming part thereof, in which—

Figure 1 is a top plan of a casing embodying my design;

Fig. 2 is a side elevation thereof;

Fig. 3 is a side elevation at right angles to the position shown in Fig. 2;

Fig. 4 is a bottom plan thereof; and

Fig. 5 is a perspective thereof.

What I claim is:

The ornamental design for a casing for a pendent switch, as shown.

RALPH A. BELMONT.
